FRANCIS B. RICHARDSON, OF BOSTON, MASSACHUSETTS.

Letters Patent No. 91,669, dated June 22, 1869.

IMPROVEMENT IN CASTING JUG-TOPS.

The Schedule referred to in these Letters Patent and making part of the same.

To all to whom these presents shall come:

Be it known that I, FRANCIS B. RICHARDSON, of Boston, in the county of Suffolk, and Commonwealth of Massachusetts, have made an invention of certain new and useful Improvements in "Jug-Tops;" and do hereby declare the following to be a full, clear, and exact description thereof, due reference being had to the accompanying drawings, making part of this specification, and in which—

Figure 1 is a perspective view, and

Figure 2, a vertical and central section of a jug-top, in the construction of which is embraced my invention.

This invention relates to improvements in the manufacture of the metallic tops of "jugs," as they are called, for the reception of sirup, milk, &c., whereby to greatly reduce the amount of labor requisite for their production, the result being a corresponding reduction in the cost of such production.

These tops are composed, as it is well known, of a tubular neck, or ring, formed with an elongated, tapering nose, for guiding the flow of liquid from the jug, and provided with a cover, hinged to the rear part of the upper surface of the tubular neck, for protecting the contents of the jug from insects or any foreign matter.

Heretofore, in most cases, one portion of this hinge, or that independent of the cover, has been cast in a separate piece, and soldered to the ring, or mouth-piece before mentioned.

My present invention or improvement consists in casting this last-mentioned portion of the hinge of a "jug-top" in one and the same piece or mass with the tubular neck, or mouth of such "top."

In the drawings before alluded to as accompanying this specification, and which illustrate my invention; the jug-top is represented at A as composed of a tubu-

lar neck, or ring b, provided with a discharging-nose, or trough, c, in the usual manner.

The cover of the jug-top is shown at d, and the male portion of its hinge at e, such portion of the hinge being provided with a knob, f, cast in one piece with it, and the whole soldered to the cover, the purpose of the knob being to facilitate the opening and closing of the cover.

The female portion of the hinge is shown at g, as cast in one piece with the tubular neck b, and composed of a narrow shelf, or lip, formed upon the upper part of such neck.

The advantages resulting from my improved construction of jug-top are, first, one casting (that is, of the independent hinge-part) is avoided; second, the soldering of one portion of the hinge to the mouth-piece is avoided; and third, the trimming and finishing of the edges of this soldered joint are avoided.

Owing to the great number of these articles cast in a large establishment, the saving of time, consequent upon the advantages before mentioned, renders my invention of considerable value.

Claim.

In jug-tops, in which one portion of the hinge which holds the cover is located upon a shelf, projecting from the rim of the tubular neck, and forming the prolongation of the hinged cover, I claim casting said shelf and hinge in one and the same piece with the tubular neck, substantially as and for the purposes herein shown and specified.

FRANCIS B. RICHARDSON.
